OF LYNN, MASSACHUSETTS, A CORPORATION OF MASSACHUSETTS

OIL VALVE

Application filed October 17, 1928. Serial No. 313,044.

This invention relates to oil valves, and in general improves the type of valve commonly termed "needle-valve."

Needle-valves are used in many connections, and are widely employed in controlling the rate of feed of liquid fuels such as hydrocarbons. The presence of small amounts of water carried along with such liquid fuels and condensing about the valve seat has given rise to faulty operation. This water shows a tendency to collect into one large drop at the valve seat. Owing to this drop's strong coherence and the relatively small annular passage opened around the needle-point when fuel is being supplied, this drop will, whenever present, interfere with the uniformity of flow through the valve and even check this flow entirely.

The object of the present invention is to provide a needle-valve having the advantage over prior types in being free from likelihood of becoming clogged by water in the manner described.

To the accomplishment of this object, and such others as may hereinafter appear, the invention comprises the features and combination of parts hereinafter described and then particularly pointed out in the appended claims.

The preferred form of the invention is shown in the accompanying drawings, in which:

Figure 1 is a view, in elevation, of the improved valve, showing also a short section of an inlet conduit and a cross-section of an outlet conduit;

Fig. 2 is a view, in vertical section on line 2-2 of Fig. 1, showing the valve closed;

Fig. 3 is a view like Fig. 2 showing the needle raised off of its seat to partially open the inlet port, but with the outlet port still closed;

Fig. 4 is a view like Fig. 2 showing the relation of the parts when both the inlet and outlet ports have been opened to the fullest extent; and

Fig. 5 is a plan view of the improved valve provided with a scale.

In the embodiment of the invention illustrated in the accompanying drawing a casing

1 is made in any suitable form to provide a valve chamber 2 having a partition at its lower end in which is an inlet port 3 for admitting liquid fuel to the chamber that is supplied through a conduit 4 connected with the casing 1 at said lower end. The port 3 is of much greater diameter than is required for the normal rate of flow of fluid, such as hydro-carbon, to maintain the burner, or other device supplied, in operation. Herein, the valve-chamber 2 is conveniently, but not necessarily, made cylindrical and is provided with a small outlet port 5 disposed in its lateral wall above the level of the inlet port 3. The port 5 communicates with a conduit 6 leading to the point of delivery at which the fuel passed through the valve is to be consumed.

A needle 7, having a conical or otherwise pointed operating end 8, is disposed lengthwise of the chamber 2 in axial alignment with the inlet port 3, against the inner rim of which said conical end 8 may seat, the needle 7 having a stem of greater diameter than that of the port 3. This seating affords a tight and effectual seal against flow of fuel through the valve.

The needle 7 is shown as longitudinally movable within the chamber 1 to afford an easily controlled means of moving its conical end 8 toward and from the inlet port 3. The needle is movable longitudinally through a plug 10 at the upper end of the casing being conveniently in screw threaded engagement with the plug which is threaded into the casing 1. The upper end of the needle stem passes loosely through the upper end of the plug 10 and leakage is prevented by packing 12 compressed by a gland nut 11 threaded exteriorly on said plug. Movement of the valve is operated by a handle 9 secured to the projecting stem of the needle 7.

In accordance with this invention, the needle 7 is provided with a portion 13 intermediate its length which closes the lateral outlet port 5 both when the pointed extremity of the needle is seated or nearly seated in the inlet port 3. This portion 13 is given a sliding fit within the chamber 2 adjacent the outlet port 5, and is mounted for move-

ment lengthwise of said chamber in unison with the needle 7 to cover and uncover said outlet port. The part 13 may be either integral with the stem of the needle 7, or through the advantageous cylindrical shape adopted herein for the chamber 2 it may be formed as a cylindrical sleeve conveniently held between a shoulder 14 formed by the lower end of the threaded portion of the needle and a collar 15 that is fixed upon the needle 7. The needle is thus free to revolve within the sleeve 13 as it is moved up or down within the chamber in operating the valve. The sleeve preferably has a tight sliding fit 15 within the casing to effectually seal the outlet port.

An important feature of the invention is the spaced relation established between the conical end 8 of the needle and the lower edge 20 of the sleeve 13. This relation is such that when the inlet port 5 is closed by the needle 7 the sleeve 13 will extend down a sufficient distance below the outlet port 5, as shown in Fig. 2, to permit a considerable upward movement of said needle and consequent substantial opening of the relatively large inlet port, before the sleeve 13 will have uncovered any part of the outlet port 5. The result of this relation is shown in Fig. 3 wherein the 25 inlet port is widely opened while the outlet port has not yet been uncovered so that, while fuel has been admitted to the chamber 2, its flow through the valve has not yet begun. It is during this relationship that any water collected around the needle-seat is given an opportunity to gravitate through the ample area offered by the opened inlet 3 and settle down through the stationary fluid in the conduit 4 to a point where it cannot cause 30 trouble. Thereafter, continued rotation of the needle 7 to lift it farther off its seat moves the lower edge of the sleeve 13 to and across the outlet port 5, leaving it wholly or partly uncovered, as may be required to obtain the 35 desired rate of flow. Thus, it is by the position of the sleeve 13 on the needle 7 that the rate of flow is controlled. The needle operates with its seat to give a positive shut-off. When the valve is set to permit flow the 40 needle is so far off its seat and the inlet port so widely opened that even considerable water standing about the said seat is ineffective to prevent adequate flow, because the opened area of the inlet port 3 is purposely 45 materially greater than the total area of the outlet port 5. Thus, ample margin is provided to care for partial blocking.

If desired, a stationary scale 16 may be applied to the valve-body, or to the gland nut 50 11, about which the illustrated handle 9 can swing as a pointer, to enable a setting of the valve found proper for a desired purpose to be quickly and surely re-established after shutting off the valve. A refinement in this 55 connection is to choose a pitch for the threads

on the valve stem such that one complete revolution of the handle 9 from shut-off position will serve to lift the needle to a height where the sleeve 13 will just begin to uncover the outlet port 5 and start the flow. Ordinarily another quarter turn of the valve stem 70 will provide sufficient flow of fuel through the valve.

The nature and scope of the invention having been indicated and the most efficient form 75 at present known having been specifically described, yet recognizing that some modifications and changes may be made without departing from its scope and spirit, what is claimed as new, is:—

1. A valve comprising an integral casing having a cylindrical chamber, closed at one end except for an inlet port and having an outlet port in its lateral wall, a plug closing the other end of the casing, a needle entering the casing through said plug having a threaded engagement with the plug, the threads on the needle terminating in a shoulder and said needle having a uniform smaller diameter below said shoulder and terminating in a conical end to seat in said inlet port, a sleeve on the needle having a sliding fit with the wall of said chamber but permitting rotation of the needle within it, said sleeve being held against axial movement on the needle by said shoulder and a collar fitted on the needle below said sleeve, and means for rotating the needle within said plug to seat and unseat its conical end in said inlet port and cause said sleeve to 95 traverse the casing past said outlet port and continually maintain axial alignment of the needle within the casing.

2. A valve comprising a casing having a cylindrical chamber and an inlet port at one 105 end and an outlet port in a lateral wall, a needle having a conical end to seat in said inlet port, a sleeve loose on the needle but in sliding engagement with the wall of said chamber to cover the outlet port, and means 110 for rotating the needle within its sleeve and moving the needle and sleeve longitudinally of the casing to open said ports and permit flow through the valve.

In testimony whereof I affix my signature. 115
LEONARD A. POPP.
